BUFFING MACHINE

Oliver W. Mojonnier, River Forest, Ill., assignor
to Mojonnier Bros. Co., a corporation of Illinois

Application August 20, 1945, Serial No. 611,545

21 Claims. (Cl. 51—103)

1

The present invention relates to buffing or polishing machines generally and has to do more particularly with machines which employ a main frame or cradle for holding tanks or vats to be worked upon by the buffing wheel. The cradle is portable and may be shifted about upon the floor to variously position the work.

One object of the invention is to so construct a buffing machine that it can be used to buff both the inside and outside of the shell of the tank.

Another object is to construct the machine so that the interior of the bottom may also be buffed.

Another object is to construct the machine so that it may buff detached bottoms or disks or other work.

With these main objects in view, the invention also contemplates novel means for rotating the shell of the tank, advancing and withdrawing the same by traction wheels traveling upon the floor, a novel head for supporting the buffing wheel, novel adjustments of the buffing wheel for working upon the cylindrical surface and upon the interior of the bottom of the tank, screw mechanism for adjusting the horizontal support which carries the buffer head, attachments to be used when buffing the disk-like bottoms separately, and certain other details which will be apparent from the following detailed description taken in connection with the accompanying drawings in which I have illustrated a preferred embodiment of the invention.

In said drawings,

Fig. 1 is a perspective view of a buffing machine constructed and arranged in accordance with the present invention, the attachment being added;

Fig. 2 is a plan view of the same with the attachment removed and showing a tank shell upon the movable cradle positioned for buffing the inside of the shell, a portion of the shell being broken away to show the buffing head which is shown in its central position within the shell;

Fig. 3 is a horizontal section of the same, the shell being removed and section being taken just below the buffing head as indicated by the line 3—3 of Fig. 4;

Fig. 4 is an end view of the same with a shell in place upon the cradle and one supporting member shown in central vertical section to show the way in which the head is raised and lowered;

Fig. 5 is a perspective view of the screw engaging nut showing the fins for retaining it in non-rotating position;

Fig. 6 is a similar view of the upper end of the

supporting member for the screw showing the slots into which the fins fit;

Fig. 7 is a vertical transverse section illustrating the head in central position, the plane of section being indicated by the line 7—7 of Fig. 2;

Fig. 8 is a similar section indicating the buffing head in position to buff the outside cylindrical surface of the tank;

Fig. 9 is a detail elevation of the buffing head, portions being broken away to show the horizontal pivotal connection;

Fig. 10 is a side elevation of the head with the buffing wheel occupying its vertical position for buffing the interior of the bottom of the tank;

Fig. 11 is a sectional view showing the forward locator or stop for engaging the edge of a tank shell, the parts being reversely positioned relative to their position in Figs. 2 and 3.

Fig. 12 is a similar view showing the rear locator or stop for engaging the bottom of the tank near its center so as to serve as a center point about which the tank may rotate, the view being indicated by the line 12—12 of Fig. 3;

Fig. 13 is a vertical section of the attachment frame and adjacent parts;

Fig. 14 is a diagram of a separated head bearing upon the supporting and driving wheels and in position to be buffed by the buffing wheel;

Fig. 15 is a cross section of the horizontal member of the attaching frame, the plane of section being indicated by the line 15—15 of Fig. 13; and

Figs. 16 and 17 are diagrams illustrating in plan the positions of the supporting wheels of the attachment and the driving wheels of the main machine, the positions of the views being indicated by the lines 16—16 and 17—17 respectively, of Fig. 14.

Throughout these several views, like characters refer to like parts.

The novel buffing machine comprises in brief a shiftable cradle A upon which the work is held, a buffing head B having a positively driven buffing wheel which may be used to buff the inside or outside of tanks, and raising and lowering mechanism C by which the head B may be adjusted. The cradle is movable about the floor of the shop where the machine is employed. An attachment D also enables the machine to be used with various other pieces of work.

The cradle A, which constitutes the main supporting frame of the work, comprises two sides 20 and two ends 21, preferably channels welded together, the ends 21 resting upon the sides 20. At an intermediate point, the sides are connected by suitable angle irons 22 welded to the bottom

flanges of the sides. These constitute the supports for the traction motor 23 and the motor 24 which drives the supporting wheels 25, 26. The motor 23 rests upon a base plate 26^a carried by the angle bars 22. The motor 24 is spaced from the supporting angle irons 22 by being bolted to the upper side of two intervening frames 27 having their under portion welded to two cross bars 27^a supported by and welded to the angle bars 22. These bars 27^a overhang the angle bars 22 and 10 thus provide a support for the frames 27.

On the under side of the frame A and near its ends are bearings 28 secured to the under side of the sides 20 in which are journaled two shafts 29 carrying traction wheels 30 which travel on the floor. Upon each shaft 29 is secured a sprocket wheel 31. Sprocket chains 32 engage these wheels and drive them through the sprocket wheels 33 mounted on the shaft of the gear reducer 34 associated with the traction motor 23. The motor 20 is reversible and hence the wheels 30 may be driven either way to shift the frame A. The motor is an electric motor and is controlled through a cable 35 running from the motor to the face of a switchboard 36 where suitable control devices are provided. When once set laterally, the cradle may be moved to and fro at will to feed the buffing wheel along the surface being buffed. The switchboard is preferably a plate of metal with the various control devices (not shown) attached thereto.

Mounted upon the upper edges of each of the ends 21 of the frame A are two bearings 37, 37, and these support the longitudinally extending shafts 38 in substantially parallel relation. The shafts 38 are mounted to rotate in these bearings. They support the wheels 25 and 26, respectively. The latter are adjustable therewith by reason of a longitudinal keyway 39 into which a key on each wheel fits. Each wheel is held in its adjusted position by a set screw 40. Each shaft 38 is also provided with a sprocket wheel 41 which is fixed to it and by which it receives power through sprocket chains 42 from the output shaft of the worm and gear speed reducer 43 associated with the motor 24, said shaft being provided with a pair of sprocket wheels 44 for the purpose.

The wheels 25, 26, which are the work-contacting elements, are relatively broad rimmed and have rubber tires so that they do not readily slip but will make firm contact with the piece of work which is to be rotated by them. Such work may be the cylindrical shell of a bottomed tank as the tank 45 shown in Figs. 5 and 6 or the open shell 46 as shown in Fig. 4. The tank shell is mounted on the wheels 25, 26, with its axis horizontal as shown. Their rotation by the motor 24 drives the shell continuously in the same direction. The motor 24 is an electric motor which is controlled through a cable 47 which leads the same as the cable 35, to the switchboard 36 upon which suitable control devices are located.

Obviously, the wheels may be spaced variable distances apart and may thus be made to dodge various fixtures and connections on the outside of the tank.

When a shell is rotated, as for example the shell 46, one end may be provided with a simple stop device like that shown in detail in Fig. 11 wherein a roller 48 mounted upon the upper end of a spindle 49 engages the end edge of the shell 46 to hold it in position. The lower end of the spindle 49 passes through a sleeve on one end of a rod 50 and is held in adjusted position by a set screw 51. The rod 50 passes through a sleeve 52.

formed upon the frame end 21 wherein it is held in adjusted position by a set screw 53.

When a bottomed shell is rotated, as for example the shell 45 of Fig. 7, then an endwise locator is provided at the bottomed tank end, such as shown in Fig. 12. The rod 55 passes down through a sleeve 56 provided with a set screw 57 for securing the rod in adjusted position. The sleeve 56 is located preferably midway between the parallel shafts 38 which carry the work engaging elements 25 and 26. Each end 21, which is a channel, has additional flanges 58, 58^a, which strengthen the member. Intermediate its upper and lower flanges and opposed to the flange 58, is a flange 59. Welded to the edge of the upper flange and to the edge of this intermediate flange 59, is a strip of metal 60 which serves as the base of the sleeve 56. At the upper end of the bar 55 is a similar transverse sleeve 61 through which a rod 62 extends which serves as the locator. The rod 62 is provided with a well rounded head 63. The rod is located to have its head 63 bear against the disk-like bottom of the bottomed shell 45 near its center so that as the disk and shell rotate, it will serve as a fixed center. The rod 62 is held in fixed adjusted position by a set screw 64 in the sleeve 61. The position of the bottomed tank 45 is indicated in Fig. 12.

Passing now to a description of the buffing wheel structure involving the head B, we have an horizontal support 65, in the form of a hollow shaft, upon the free end of which the head is mounted. The head and the forward end of the shaft are mounted so as to be entered into the open end of the shell when it is in working position. The buffing wheel is positively driven by an electric motor 67^a, both wheel and motor being moved as a unit.

The horizontal support 65 terminates at its free end in head plate 66 having a reduced portion or pindle 67. The head plate and pindle are adapted to receive a yoke 68 having a cross piece 69 uniting two sides 70, 70. The cross piece 69 is provided with a central bearing 71 adapted to engage the pindle 67 on the head plate 66. A ring 72 is fixed to the end of the pindle by any suitable device, as for example a set screw 73. The yoke 68 rotates upon the pindle 67. It may be fixed in different rotary positions by a series of bolts or pins 74 passing through cooperating holes in the head plate 66 into threaded openings in the yoke cross piece 69. Upon loosening the pins, the yoke 68 may be rotated to any desired adjusted position and then the pins or bolts 74 reinserted and screwed home. Thus an adjustment of the buffer head about the longitudinal axis of the supporting shaft 65 is provided.

Within the yoke member 70 are the plates 75 which, together with the end 76, form an enclosing casing for the motor 67^a. This enclosure has oppositely extending trunnions 77 which pass into bearings in the yoke members 70. Straps 78 are welded or otherwise secured to the top edges of the yoke member 75. They also carry pins 79^a which pass through them into threaded engagement with the motor 67^a to hold the latter in place. Thus the motor is capable of rotary adjustment about the pivotal axis provided by the trunnions 77. It may be held in different adjusted positions by means of pins 79 passing through openings in the one of the yoke plates 70 into tight engagement with holes in the motor frame member 75. The pins or bolts may be provided with threads and pass into engagement

with threaded openings in the frame member if desired.

The motor 67^a drives the buffing wheel 80 mounted on the free end of a buffer shaft 81 adapted to rotate in bearings 82 projecting from the motor frame. A multiple belt 83 passes over grooved pulleys 84, 85, upon the motor shaft and the shaft 81, respectively. A fender 86 projects from the adjacent end of the motor frame member 76 out over the wheel 80 as a protective measure.

The motor 67^a is an electric motor and is provided with a supply cable 87 having slack sufficient to care for it in its different positions and leading off to the far side of the switchboard 36, as the parts are viewed in Fig. 1, where it is supplied with suitable starting and stopping devices (not shown).

Coming now to the raising and lowering mechanism C by which the horizontal support 65 is firmly supported with its free end bearing the head B, it will be noted that there are two upright posts 88, 88, seated down in the ground to a depth of several feet, depending upon the height to which the head is to be raised, which serve as the basic supporting members. Within these there are two telescopic members 89 which support the horizontal member 65. All these members are preferably hollow, the member 65 for lightness, and the others to receive the screws 90. The upper ends of the posts 89 are cut to fit against the under side of the horizontal member 65 and are securely welded thereto. On the upper side of the member 65 are the saddles 91 which are firmly secured at their ends thereto by machine screws 92.

A thrust bearing 94 is secured, by welding, to each saddle 91 and the associated portion of the horizontal supporting member 65. It extends above and below the saddles 91 as shown. It will suffice to describe one.

The screw 90 is journaled for rotation within the gearing 94 and is held in position by an upper collar 95 and a lower collar 96. These collars are pinned to the shaft so as to rotate with it. At a point well down within the post 88, is a nut 97 which is supported on a fixed hollow post 98 and held against rotation by lateral fins 99 entering slots 100 in the post 98. The screw 90 is threaded into the non-rotating nut. Hence, as the screw 90 is rotated, it will move up or down in the nut 97 according to the direction of rotation. At the bottom the posts 88 and 98 are closed with a stop plate 101 welded to the ends.

By rotating the screws 90 equal amounts in one direction, the support 65 is raised; and by rotating the same equal amounts in the opposite direction, it is lowered. To bring about these equal rotations, I employ a reversible electric motor 102. This motor moves up and down with the horizontal support 65 to which it is attached by suitable frame members 103, 103, welded thereto at their lower ends, and tied at their upper ends by straps 104, 104, connected to the gearing frame 105, which is secured to the other side of the horizontal support 65 with intervening blocks 106. The gearing frame 105 carries a suitably journaled shaft 107 which spans the opening in the frame. The shaft 107 is driven from the motor 102 through gearing including a small sprocket wheel 108 on the motor shaft, a large sprocket wheel 109 on the shaft 107, and an interconnecting sprocket chain 110. Other sprocket chains 111 extend from small sprocket wheels on the shaft 107 to sprocket wheels 112

secured to the upper ends of the screws 90. The motor 102 is a reversible electric motor and is supplied with current through an electric cable, a portion of which is designated 113. It communicates with suitable stopping and starting control devices upon the face of the board 36. Each sprocket chain 111 travels over a belt tightener 114 located upon outwardly extending arms 114^a of the frame 105. Thus, by means of the motor 102, it is possible to raise or lower the buffer head.

I also preferably employ a telescopic means for guiding and stopping the cradle when it overruns its limit. The means is located between the cradle A and the fixed portion of the machine. The device is shown more particularly in Figs. 2 and 3. As there shown, I employ two open ended tubes 115, 116, with a telescoping intermediate tube or rod 117, provided with a collar 118 held in adjusted position by a set screw 119. These are located in a longitudinal line when the cradle is properly placed. The tube 115 passes through a suitable opening in that end 21 of the frame A adjacent to the posts 88, and is secured in the opening either by a tight fit or otherwise, as desired. On the other hand, the tube 116 is passed through suitable sleeves 120 bracketed upon transverse supports 121 welded to the posts 88 and extending to the board 36, as shown.

In operation, as the cradle A approaches the left-hand post 88, as the parts are viewed in Fig. 3, the adjacent end 122 of the tube 115 may engage the collar 118 and then shove the rod 117 along in the tube 116 until it strikes the closed end 123 of the tube, thereby blowing a fuse or a circuit breaker as the case may be, unless the traction motor 23 is reversed or stopped by the time it reaches that point. Thus the telescopic tube arrangement is utilized in the control of the advance of the cradle A. And, of course, it may be moved in the opposite direction until the rod 117 separates from either tube 115 or 116, whereupon the cradle may be moved laterally by a hoist or otherwise into the position where the head 12 will be in line to buff the outside of the tank or do other work, as for example in Fig. 8. By removing the intermediate telescopic rod 117 altogether from the equipment, the buffing machine may still be used. The telescopic guiding and stopping means may be discarded altogether and the various other parts will work as outlined. It will ordinarily be located for one position of the work, such as the dotted line position of the brush and head of Fig. 7. It is so located because the bulk of the work calls for the operation of the brush in that position.

When the attachment D is to be placed upon the machine, the endwise locator, shown in Fig. 12, is removed and the auxiliary frame of the attachment is put in place. This frame comprises a horizontal member 124, projecting from the end of the main frame, and a downwardly extending post 125 which, when in position, rests upon the floor. The post 125 is adapted to pass through the sleeve 56 and to be secured, if desired, by the set screw 57. At its upper end it is welded between two longitudinally extending members 126. These members are angle irons which are welded to a plate 127 at one end, and at the other to a sleeve 128 provided with a set screw 129. The resulting structure constitutes a telescopic member which receives a telescoping rod 130 which terminates in a transverse sleeve 131 provided with a set screw 132. Within the sleeve 131 is a vertical rod 133 which carries a

yoke 134. The yoke 134 is provided at its ends with bearings for the work engaging rollers 135. The plate 127 when in position overlies the upper flange of the end 21. By means of the set screws 129 and 132, the rollers 135 may be set in different positions according to the work being worked upon.

The work which may be a dished disk-like member, like the tank end 136 (shown in Fig. 14) is provided with a central temporary aperture 137 for the passage of an additional support. This support comprises a rod 138 which constitutes a vertical pivotal point for the work. The upper portion of the rod 138 is reduced in diameter to fit loosely within the hole in the work 136, and at its lower end the rod passes adjustably within the upright sleeve 139 and is held in adjusted position by a set screw 140. The sleeve 139 is welded to the upper clamping plate 141 which cooperates with a lower clamping plate 142 and clamping bolts 143 to set the supporting rod 138 in any desired position along the horizontal frame member 124, to suit the position of the work.

The two figures (Figs. 16 and 17) show the relative positions of the supporting rollers or wheels 135, the driving wheels 25 of which two come into play upon a disk piece of work, and the buffing wheel 80. To bring about ready rotation and not wear upon the work, a washer 144 may be employed. It is placed upon the upper end of the supporting pivot rod 138 and bears upon the shoulder 145 formed where the rod 138 is reduced in diameter. When the perforated piece of work is completely buffed, the hole 137 may be plugged.

The switchboard 36 is supported on two channel uprights 146 in parallelism to the main posts 88. The same is held to the posts 88 by straps 121, 121, welded thereto at their ends. The telescoping tubular member 89 is provided in each instance with a hand hole 147 through which access may be had to the collars 96 and adjacent parts within the post.

The cables 35, 87, 47 and 113 are provided with sufficient slack to allow for the several adjustments occasioned by the motors 23, 67, 24 and 102, respectively. These cables extend through suitable openings (not shown) in the switchboard 36 and, as before stated, are connected to suitable control devices. By properly manipulating these control devices (not shown), the machine may be operated in the manner indicated.

Suitable holes 148 are provided in a lower flange of the end 21 to permit of ease in attaching tackle to move the cradle laterally.

The parts are preferably metal so as to be welded together, although other means of connecting may be employed if desired.

It may be noted also that in buffing the inside of a tank, the buffing wheel 80 may be variously positioned. Thus, it may be placed almost directly opposite the supporting wheels so that the latter will furnish resistance to its pressure. For example, it may be positioned opposite the wheels 26 as indicated by the dotted lines 149 in Fig. 7. Likewise, it might be placed opposite the wheels 25. Again in buffing the bottom of a bottomed tank, it may be as in Fig. 10 where it would encounter the tank bottom as indicated by the full line. Obviously, in feeding the tank along as the interior cylindrical surface is being buffed, as shown in the dotted line position of Fig. 7, indicated by the line 149, the traction motor 23 would come into play. Likewise, in feeding the

tank as the exterior is being buffed, as shown in Fig. 8, the traction motor would still be relied upon to perform the feeding operation. Whereas, in feeding the tank so as to buff the interior bottom surface, the vertical motor 102 would come into play. All of these various operations will at once be obvious to a worker in this art.

Ordinarily, the buffing head B occupies the position of Fig. 9. This is the position occupied when the interior of the tank is to be buffed. When the bottom is to be buffed, the head is shifted by withdrawing the bolts 79 and replacing them when moved to the correct position. If an angular position is desired, other than a right angular position, then extra holes 79 may be drilled through the plates 70 and into the plates 75 to suit the particular angle desired. When it comes to shifting the parts for outside buffing, as indicated in Fig. 8, then the head B is shifted from the position of Fig. 9 into the position of Fig. 8, by removing and replacing the bolts 74 passing through openings in the plate 66, as will be apparent.

When buffing the outside of the tank, I ordinarily employ a plurality of resisting members 150 provided with rollers 151 at their upper ends, and seated at their lower ends in suitable sockets provided by holes 152 in the upper flanges of the side members 20 of the cradle A and depressions 153, in the lower flanges of the same members. These resisting members are sufficiently stout to bear the pressure exerted by the brush 80 while buffing the outside of the tank.

Other devices may be used upon tanks of thin material to reinforce them as may be required.

Although the term "tanks" has been used throughout the preceding description, yet it will be understood that the particularly buffing machine is useful in polishing various surfaces, including tanks, vats and the like. The word "tanks" is applied in certain trades to receptacles intended primarily for storage purposes, while in the same trade the term "vats" is applied to receptacles employed for processing purposes.

The terms used herein, both in the specification and claims, are used in an instructive sense and not in any limiting sense. By the term "buffing" in its various forms, it is intended to include grinding, polishing, and the like.

It will be understood, too, that changes may be made in the specific matter herein disclosed and, accordingly, the terms of the appended claims are relied upon to cover all such alterations and modifications which lawfully come within the spirit and scope of the invention.

I claim:

1. A device of the class described comprising a cradle for holding the cylindrical shell of a tank with its axis horizontal, said cradle comprising a plurality of rotary shell contacting elements, said elements having a plurality of axes lying in parallel relation to said shell axis, means mounted on said cradle and operative to rotate said shell about its axis while in engagement with said shell contacting elements, a horizontal support having a projecting end adapted to enter the shell, a positively driven buffing wheel mounted on the free end of said support and operative to buff the interior surface of the shell, means for readily shifting said cradle to and from relative to said horizontal support to give said wheel its working feed, and means for readily raising and lowering said support to permit of its ready introduction into the interior of the shell.
2. A device of the class described comprising

a cradle for holding the cylindrical shell of a tank with its axis horizontal, said cradle comprising a plurality of rotary shell contacting elements, said elements having a plurality of axes lying in parallel relation to said shell axis, means mounted on said cradle and operative to rotate said shell about its axis while in engagement with said shell contacting elements, a horizontal support having a projecting end adapted to enter the shell, a positively driven buffing wheel mounted on the free end of said support and operative to buff the interior surface of the shell, means for readily shifting said cradle to and fro relative to said horizontal support to give said wheel its working feed, means for readily raising and lowering said support to permit of its ready introduction into the interior of the shell, and means for engaging said shell at its opposite ends to position the same upon said cradle.

3. A device of the class described comprising a cradle for holding the cylindrical shell of a tank with its axis horizontal, said cradle comprising a plurality of parallel rotary shafts parallel to the axis of said shell, a plurality of wheels on said shafts, means mounted on said cradle and operative to rotate said shell about its axis while in engagement with said wheels, a horizontal support having a projecting end adapted to enter the shell, a positively driven buffing wheel mounted on the free end of said support and operative to buff the interior surface of the shell, means for readily shifting said cradle to and fro relative to said horizontal support to give said wheel its working feed, and means for readily raising and lower said support to permit of its ready introduction into the interior of the shell.

4. A device of the class described comprising a cradle for holding the cylindrical shell of a tank with its axis horizontal, said cradle comprising a plurality of parallel rotary shafts parallel to the axis of said shell, a plurality of wheels on said shafts, means mounted on said cradle and operative to rotate said shell about its axis while in engagement with said wheels, a horizontal support having a projecting end adapted to enter the shell, a positively driven buffing wheel mounted on the free end of said support and operative to buff the interior surface of the shell, means for readily shifting said cradle to and fro relative to said horizontal support to give said wheel its working feed, means for readily raising and lowering said support to permit of its ready introduction into the interior of the shell, and means for engaging said shell at its opposite ends to position the same upon said cradle.

5. A device of the class described comprising a cradle for holding the cylindrical shell of a tank with its axis horizontal, said cradle comprising a plurality of parallel rotary shafts parallel to the axis of said shell, a plurality of wheels on each of said shafts mounted to be variably spaced apart, means for driving said wheels to rotate said shell about its axis, a horizontal support having a projecting end adapted to enter the shell, a positively driven buffing wheel mounted on the free end of said support and operative to buff the interior surface of the shell, means for readily shifting said cradle to and fro relative to said horizontal support to give said wheel its working feed, and means for readily raising and lowering said support to permit of its ready introduction into the interior of the shell.

6. A device of the class described comprising a cradle for holding the cylindrical shell of a tank with its axis horizontal, said cradle comprising a

plurality of parallel rotary shafts parallel to the axis of said shell, a plurality of wheels on each of said shafts mounted to be variably spaced apart, means for driving said wheels to rotate said shell about its axis, a horizontal support having a projecting end adapted to enter the shell, a positively driven buffing wheel mounted on the free end of said support and operative to buff the interior surface of the shell, means for readily shifting said cradle to and fro relative to said horizontal support to give said wheel its working feed, means for readily raising and lowering said support to permit of its ready introduction into the interior of the shell, and means for engaging said shell at its opposite ends to position the same upon said cradle.

7. A device of the class described comprising a cradle for holding the cylindrical shell of a bottomed tank with its axis horizontal, said cradle comprising a plurality of rotary shell contacting elements, said elements having a plurality of axes lying in parallel relation to said shell axis, means mounted on said cradle and operative to rotate said shell about its axis while in engagement with said shell contacting elements, a horizontal support having a projecting end adapted to enter the open end of the tank, a movable member carried upon the free end of said horizontal support, a buffing wheel and driving motor therefor pivotally mounted in said member, means for adjusting said wheel and motor to different positions to enable said wheel to buff the interior walls and the bottom of the tank, means for readily shifting said cradle to and fro relative to said horizontal support, and means for readily raising and lowering said support, whereby said buffing wheel may be positioned for work upon the interior walls and bottom of the tank.

8. A device of the class described comprising a cradle for holding the cylindrical shell of a bottomed tank with its axis horizontal, said cradle comprising a plurality of rotary shell contacting elements, said elements having a plurality of axes lying in parallel relation to said shell axis, means mounted on said cradle and operative to rotate said shell about its axis while in engagement with said shell contacting elements, a horizontal support having a projecting end adapted to enter the open end of the tank, a movable member carried upon the free end of said horizontal support, a buffing wheel and driving motor therefor pivotally mounted in said member, means for adjusting said wheel and motor to different positions to enable said wheel to buff the interior walls and the bottom of the tank, means for readily shifting said cradle to and fro relative to said horizontal support, means for readily raising and lowering said support, whereby said buffing wheel may be positioned for work upon the interior walls and bottom of the tank, a locator positioned at the end of said cradle distant from said horizontal support adapted to be vertically adjusted to engage the center of the bottom of the tank, and a companion stop device located upon the cradle at the opposite end of the tank, the locator and stop device serving to position the tank upon the cradle.

9. A device of the class described comprising a cradle for holding the cylindrical shell of a bottomed tank with its axis horizontal, said cradle comprising a plurality of rotary shell contacting elements, said elements having a plurality of axes lying in parallel relation to said shell axis, means mounted on said cradle and operative to rotate said shell about its axis while in engagement with

said shell contacting elements, means for moving said cradle to and fro horizontally, a horizontal support having a projecting end adapted to enter the shell, means for moving said horizontal support to and fro vertically, a head plate secured to the end of said horizontal support, a yoke pivotally mounted on said head plate, a buffering wheel and driving motor therefor pivotally mounted upon said yoke, means for adjusting said yoke relative to said head plate, and means for adjusting said buffering wheel relative to said yoke, whereby said buffering wheel may be positioned for work upon the exterior and the interior and the bottom of the tank.

10. A device of the class described comprising a cradle for holding the cylindrical shell of a bottomed tank with its axis horizontal, said cradle comprising a plurality of rotary shell contacting elements, said elements having a plurality of axes lying in parallel relation to said shell axis, means mounted on said cradle and operative to rotate said shell about its axis while in engagement with said shell contacting elements, a horizontal support having a free projecting end, a head plate fixed to the free end of said support, a yoke pivoted to said head plate, a movable frame having pivotal engagement with said yoke, said pivotal axes being at right angles to each other, a buffering wheel and an electric motor carried by said movable frame, a buffer shaft geared to said motor and supported by said movable frame, a buffering wheel secured to the free end of said buffer shaft, adjusting means between said head plate and yoke for holding said yoke in different adjusted positions, adjusting means between said yoke and movable frame for holding said movable frame in different adjusted positions relative to said yoke, means for readily adjusting said cradle toward and from said horizontal support, and means for readily adjusting said horizontal support up and down.

11. A device of the class described comprising a cradle for holding the cylindrical shell of a tank with its axis horizontal, said cradle comprising a plurality of rotary shell contacting elements, said elements having a plurality of axes lying in parallel relation to said shell axis, means mounted on said cradle and operative to rotate said shell about its axis while in engagement with said shell contacting elements, a horizontal support having a projecting end adapted to enter the shell, a buffering wheel mounted on the projecting end of said horizontal support, means for readily raising and lowering said horizontal support to position said buffer wheel vertically, traction wheels on the under side of said cradle, and means for driving said traction wheels to position said cradle horizontally.

12. A device of the class described comprising a cradle for holding the cylindrical shell of a tank with its axis horizontal, said cradle comprising a plurality of parallel rotary shafts parallel to the axis of said shell, a plurality of wheels on said shafts, means mounted on said cradle and operative to rotate said shell about its axis while in engagement with said wheels, a horizontal support having a projecting end adapted to enter the shell, a buffering wheel mounted on the projecting end of said horizontal support, means for readily raising and lowering said horizontal support to position said buffer wheel vertically, traction wheels on the under side of said cradle, and means for driving said traction wheels to position said cradle horizontally.

13. A device of the class described comprising

a main supporting frame, a plurality of rotary work engaging elements upon said main frame, said elements being mounted for rotation upon parallel axes, means mounted on said main frame operable to rotate the work resting upon said elements, a pair of fixed vertical posts, vertical supports guided upon said posts, a horizontal support fixed to said vertical supports and having a free projecting end, screw and nut mechanism for raising and lowering said vertical supports and said horizontal support with reference to said posts, a positively driven buffering wheel mounted on the free end of said horizontal support, and means for shifting said main frame toward and from said posts.

14. A device of the class described comprising a main supporting frame, a plurality of rotary work engaging elements upon said main frame, said elements being mounted for rotation upon parallel axes, means mounted on said main frame operable to rotate the work resting upon said elements, a pair of fixed vertical posts, vertical supports guided upon said posts, a horizontal support fixed to said vertical supports and having a free projecting end, a screw journaled for rotation upon each of said vertical supports, cooperating non-rotatable nuts into which said screws are respectively threaded, posts for supporting said nuts, a motor and gearing for rotating said screws equal amounts to raise and lower said horizontal support, a positively driven buffering wheel mounted on the free end of said horizontal support, and means for shifting said main frame toward and from said posts.

15. A device of the class described comprising a cradle for holding the cylindrical shell of a tank with its axis horizontal, said cradle comprising a plurality of parallel rotary shafts parallel to the axis of said shell, a plurality of wheels on said shafts, means mounted on said cradle and operative to rotate said shell about its axis while in engagement with said wheels, a pair of fixed vertical posts, vertical supports guided upon said posts, a horizontal support fixed to said vertical supports and having a free projecting end, screw and nut mechanism for raising and lowering said vertical supports and said horizontal support with reference to said posts, a positively driven buffering wheel mounted on the free end of said horizontal support, and means for shifting said cradle toward and from said posts.

16. A device of the class described comprising a main supporting frame, a plurality of rotary work engaging elements upon said main frame, said elements being mounted for rotation upon substantially horizontal parallel axes, an auxiliary frame projecting from the end of said main frame, auxiliary rotary work engaging elements upon said auxiliary frame, means on said main frame for positively rotating the elements thereon, a vertical pivotal point removably attached to said main frame approximately midway between said parallel axes, upon which point the work may be mounted for rotation, a horizontal support having a free projecting end extending toward said auxiliary frame and overlying said work, a positively driven buffering wheel mounted upon the free end of said horizontal support and adapted to rotate in a substantially vertical plane, means for shifting said main frame together with said auxiliary frame to and fro relative to said buffering wheel, and means for vertically adjusting said buffering wheel into and out of buffering engagement with said work.

17. A device of the class described comprising

ing a main supporting frame, a plurality of work engaging elements upon said main frame, said elements being mounted for rotation upon parallel substantially horizontal axes, means on said main frame for positively rotating said elements, a laterally fixed horizontal support having a free projecting end, a buffing wheel mounted upon said free projecting end, means for shifting said main frame toward and from said buffing wheel, means for vertically adjusting said buffing wheel, and a telescopic guiding and stopping means operative between said movable main frame and said fixed horizontal support.

18. A device of the class described comprising a movable main supporting frame, a plurality of rotary elements upon said frame for engaging the work, said elements being mounted for rotation upon parallel axes, means mounted upon said main frame operable to rotate the work resting upon said elements, a pair of fixed vertical posts, vertical supports guided upon said posts, a horizontal support fixed to said vertical supports and having a free projecting end, screw and nut mechanism for raising and lowering said vertical supports and said horizontal support with reference to said posts, a positively driven buffing wheel mounted on the free end of said horizontal support, and means for shifting said main frame toward and from said posts.

19. A device of the class described comprising a movable main supporting frame, a plurality of rotary elements upon said frame for engaging the work, said elements being mounted for rotation upon parallel axes, means mounted upon said main frame operable to rotate the work resting upon said elements, a pair of fixed vertical posts, vertical supports guided upon said posts, a horizontal support fixed to said vertical supports and having a free projecting end, a screw journaled for rotation upon each of said vertical supports, cooperating non-rotatable nuts into which said screws are respectively threaded, posts for supporting said nuts, a motor and gearing for rotating said screws equal amounts to raise and lower said horizontal support, a positively driven buffing wheel mounted on the free end of said horizontal support, and means for shifting said main frame toward and from said posts.

20. A device of the class described comprising a movable main supporting frame, a plurality of rotary elements upon said frame for engaging the work, said elements being mounted for

rotation upon parallel axes, means mounted upon said main frame operable to rotate the work resting upon said elements, means for moving said supporting frame to and fro horizontally, a horizontal support having a projecting end, means

- 5 for moving said horizontal support up and down, a head plate secured to said projecting end, a yoke pivotally mounted on said head plate, a buffing wheel and driving motor therefor pivotally mounted upon said yoke, and means for adjusting said yoke relative to said head plate, whereby the buffing wheel may be properly positioned relative to the work.

21. A device of the class described comprising a movable main supporting frame, a plurality of rotary elements upon said frame for engaging the work, said elements being mounted for rotation upon parallel axes, means mounted upon said main frame operable to rotate the work resting upon said elements, a horizontal support having a projecting end, a head plate secured to said projecting end, a yoke pivoted to said head plate, a movable frame having pivotal engagement with said yoke, said pivotal axes being at right angles to each other, a buffing wheel and an electric motor carried by said movable frame, a buffer shaft geared to said motor and supported by said movable frame, a buffing wheel secured to the free end of said buffer shaft, adjusting means between said head plate and yoke for holding said yoke in different adjusted positions, means for readily adjusting said main supporting frame toward and from said horizontal support, and means for readily adjusting said horizontal support up and down.

OLIVER W. MOJONNIER.
